UNITED STATES PATENT OFFICE.

DAVIS A. PICKENS, OF JACKSON, MISSISSIPPI.

RAILWAY BRIDGE SWITCH.

Application filed June 16, 1924. Serial No. 720,246.

To all whom it may concern:

Be it known that I, DAVIS A. PICKENS, residing at Jackson, in the county of Hinds and State of Mississippi, and a citizen of the United States, have invented certain new and useful Improvements in Railway Bridge Switches, of which the following is a specification, reference being had to the accompanying drawings, forming a part thereof.

10 My invention relates to railway bridge switches which are designed mainly for temporary or occasional use. It is frequently desirable to have a switch which can be put in use easily when it is necessary to switch trains around wrecks or make use of steam shovels and other construction or repair machinery.

15 An object of the invention is to provide a switch which may be easily installed without cutting or otherwise changing the main line track;

Another object is to provide a switch which may be turned back easily and quickly so as to permit the main line track to be used without interference or danger;

20 A further object is to provide a bridge switch having members which will be safely locked in place when the bridge switch is to be used;

25 And a further object is to provide a switch of ample strength which can be made of very light construction so that it can be carried on tool cars and be handled without difficulty.

30 With these objects and other objects hereinafter set forth in view, the invention comprises the construction and combination of elements hereinafter described and claimed.

Referring to the drawings:

35 Figure 1 is a plan view of a railway track showing the bridge switch in use;

Figure 2 is a plan view of the railway track showing bridging members of the switch turned back out of use;

40 Figure 3 is an elevation of the first inside rail bridge over member with a partial section along line 3—3 of Figure 1;

Figure 4 is a view of the under side of the second inside rail bridge over member;

45 Figure 5 is an end elevation of two bridge over members with a partial section taken along line 6—6 of Figure 1;

Figure 6 is an elevation of the second inside bridge over member with a section taken along line 6—6 of Figure 1;

50 Figure 7 is a vertical sectional view of

the first inside rail bridge over member along line 7—7 of Figure 1; and

Figure 8 is a vertical sectional view of the outside rail bridge over member along 60 line 8—8 of Figure 1.

Referring to the drawings, 1 indicates an inside rail and 2 an outside rail of a railway track. 3 indicates an inside rail bridge over member having trunnion ends 4 and 5 65 supported in the end blocks 6 and 7 which are mounted on the railway ties or other supports. End blocks 6 and 7 are designed particularly to combine strength, lightness and ease of attachment to the railway ties 70 or other supports. The bridge over member 3 carries the rail portion 8 which is provided with downwardly extending plates 9 and 10 adapted to bear against the sides of rails 1 and 11, rail 11 being one of the auxiliary rails used in connection with the bridge switch. Plates 9 and 10 serve as a bracing means to secure member 3 against wheel thrust. As shown in Figure 3, the rail portion 8 is thick the major part of its 75 length so as to be able to support railway rolling stock while the ends of said rail portion taper down so as to present little resistance to the passage of wheels. The bridge over member 3 has the open spaces 80 12 and 13 in order to allow ample clearance for the upwardly extending portions of the end blocks 6 and 7 when the member 3 is 85 to be turned back as shown in Figure 2. The bridge over member 3 is preferably 90 shaped as shown in order to combine strength with lightness.

The outside rail bridge over member 14 is similar in construction and operation to member 3 except that the downwardly extending plates 9 and 10 are not necessary and a groove 22 must be provided for the passage of wheel flanges. The member 14 is provided with trunnion ends 16 and 17 supported in end blocks 18 and 19. The member 14 has the openings 20 and 21 to allow clearance for the upwardly extending portions of end blocks 18 and 19. The rail portion 15 is similar in shape to rail portion 8 of member 3, but a groove 22 is 105 provided just inside of rail portion 15 in order to permit passage of wheel flanges. Rail portion 15 is flat on its under side so as to fit down on parts of rails 2 and 23, rail 23 being a second auxiliary rail used 110 in connection with the bridge switch. The under side of member 14 is preferably

shaped to provide a ridge 35 adapted to bear against the sides of rails 2 and 23 to serve as a bracing means to secure member 14 from being thrust outward when wheels 5 pass over the switch.

The second inside rail bridge over member 24 is provided with a rail portion 25 tapered at its ends similar to rail portions 8 and 15. The main part of member 24 may be of 10 less height than the rail portion 25 in order to permit the passage of wheel flanges or a groove similar to groove 22 may be provided. The member 24 is supported on the block 26 and is pivoted on a bolt 27. Secured to the under side of member 24 are block-like portions 28 and 29 which are 15 adapted for sliding on a supporting block 30 mounted on a railway tie or other support. The block-like portion 28 is arranged 20 to fit against the side of rail 1 when the member 24 is in use (the position shown in Figure 1) thereby serving as a bracing means for holding member 24 against wheel thrust; block-like portion 28 also serves 25 as a stop acting against block 26 when member 24 is in the position shown in Figure 2, thereby serving to hold rail portion 25 substantially parallel with rail 1 when the switch is not in use. Rail portion 25 is 30 adapted to rest on rails 23 and 31, rail 31 also being an auxiliary rail used in connection with the bridge switch.

32, 33, and 34 indicate bracing wedges 35 adapted to aid in holding and positioning the auxiliary rails 11, 23 and 31.

As shown in Figure 2, when the bridge over members 3, 14 and 24 are turned back, the main line rails 1 and 2 are perfectly clear. As shown in Figure 1, when the 40 bridge over members are placed in use, a strong and safe bridge over switch having its members secured against wheel thrust is provided.

It should be noted that the supporting 45 blocks for the three rail bridging members are of such shape that they may be easily spiked or otherwise secured to the railway ties or other supports. As provision is made for transferring wheel thrust from the rail bridging members to the main line rails themselves, the supporting blocks for these members need not be so securely fastened down as would otherwise be the case.

55 It should be understood that any change in the shape of the switch members may be made for the purpose of lightening or strengthening them without affecting the essential features of this invention.

60 Having thus described my invention, what I claim is:

1. In a railway bridge switch, the combination with main line rails and auxiliary rails forming a switch track of three rail bridging members, each comprising a sup-

porting body and a rail portion having tapered ends secured thereto, trunnions and supports for two of said rail bridging members arranged to permit these bridging members to be turned back in order to leave the 70 main line rails clear or to be turned over so as to place the rail portion of each on top of a main line rail and an auxiliary switching rail in order to cause a wheel to pass from one rail to the other, and a pivot and 75 supporting means for the third rail bridging member arranged to permit this member to be swung back on its pivot in order to leave the main line rail clear or to be swung forward so as to place its rail portion on 80 top of parts of two auxiliary switching rails and the main line rail in order to cause a wheel to pass from one auxiliary rail to the other.

2. In a railway bridge switch, the combination with main line rails and auxiliary rails forming a switch track of three rail bridging members, each comprising a supporting body and a rail portion having tapered ends secured thereto, trunnions secured to two of said rail bridging members arranged to permit these bridging members to be turned back in order to leave the main line rails clear or to be turned over so as to place the rail portion of each on top of a main line rail and an auxiliary switching rail in order to cause a wheel to pass from one rail to the other, trunnion supports shaped to be easily securable to the main rail supports, a pivot for the third rail 90 bridging member arranged to permit this member to be swung back on its pivot in order to leave the main line rail clear or to be swung forward so as to place its rail portion on top of parts of two auxiliary 95 switching rails and the main line rail in order to cause a wheel to pass from one auxiliary switching rail to the other, and supporting means for the third rail bridging member and its pivot shaped to be easily 100 securable to the main rail supports.

3. In a railway bridge switch, the combination with main line rails and auxiliary rails forming a switch track of three rail bridging members, each comprising a supporting body and a rail portion having tapered ends secured thereto, trunnions and supports for two of said rail bridging members arranged to permit these bridging members to be turned back in order to leave the main line rails clear or to be turned over so as to place the rail portion of each on top of a main line rail and an auxiliary switching rail in order to cause a wheel to 115 pass from one rail to the other, a pivot and supporting means for the third rail bridging member arranged to permit this member to be swung back on its pivot in order to leave the main line rail clear or to be swung forward so as to place its rail portion on 120 the main line rail in order to cause a wheel to pass from one auxiliary rail to the other, and supporting means for the third rail bridging member and its pivot shaped to be easily 125 securable to the main rail supports.

top of parts of two auxiliary rails and the main line rail in order to cause a wheel to pass from one auxiliary switching rail to the other, and bracing means secured to each 5 rail bridging member adapted to bear against parts of rails to secure the members against wheel thrust.

4. In a railway bridge switch, the combination with a main line rail and auxiliary 10 switching rails of a rail bridging member having a supporting body and a rail portion having tapered ends secured thereto, a vertical pivot and horizontal supporting means arranged to be mounted outside a main line rail so as to permit the rail bridging member to be swung back on its pivot in order 15 to leave the main line rail clear or to be swung forward so as to place its rail portion on top of parts of the auxiliary switching rails and the main line rail in order to cause a wheel to pass from one auxiliary switching rail to the other, a check block secured to the under side of the rail bridging member adapted to bear against the main line rail when the member is in its forward position, and a block secured to the rail support 20 in position to be struck by the check block when the rail bridging member is turned back.

25

5. In a railway bridge switch, the combination with a main line rail and auxiliary switching rails of a rail bridging member having a supporting body and a rail portion 30 having tapered ends secured thereto, a vertical pivot and horizontal supporting means arranged to be mounted outside a main line rail so as to permit the rail bridging member to be swung back on its pivot in order 35 to leave the main line rail clear or to be swung forward so as to place its rail portion on top of parts of the auxiliary switching rails and the main line rail in order to cause a wheel to pass from one auxiliary switching rail to the other, a check block secured to the under side of the rail bridging member adapted to bear against the main line rail when the member is in its forward position, and a block secured to the rail support 40 in position to be struck by the check block when the rail bridging member is turned back.

In testimony whereof I hereunto affix my signature.

DAVIS A. PICKENS.
